INK DISTRIBUTION SYSTEM

Lynn B. Case, New Brunswick, N. J., assignor to
John Waldron Corporation, New Brunswick,
N. J., a corporation of New Jersey

Application May 18, 1940, Serial No. 335,924

8 Claims. (CL 101—216)

This invention relates to ink distribution systems for printing presses, particularly of the letterpress type.

Heretofore, commercial letterpress printing has involved the use of printing inks which have the necessary fluidity and working consistency at normal press room temperatures. The ink is wet when printed on the paper and the setting or drying of the print is effected by oxidation or polymerization of an oily constituent of the ink, or by evaporation of solvents or carriers from the ink or by absorption of the ink into the paper, or by a combination of two or more of these. Newspaper printing according to this process is objectionable in that the first impression printing on one side of the paper is inferior to the second impression printing on the other side of the paper; smearing and marring occur frequently during passage of the printing web over angle bars and folders; offsetting of the printing on to the impression roller or tympan of the press occurs and the smearing tendency of newspaper printing soils the hands and clothes of the readers. High speed letterpress printing on comparatively non-absorbent paper stock with quite fluid inks compounded from pigments, binders and volatile solvents requires heating of the web after each impression in order that most of the solvent may be driven off and the print dried sufficiently to permit immediate second impression or multi-color printing and handling of the printed matter without serious smearing, offsetting and damage to the print. In very high speed work, use is often made of inks having solvents which are volatile only at high temperatures and an intense heating of the printed web is carried out after each impression to drive off solvents, the heating being at temperatures which would inevitably burn the paper if not carried out very quickly. Such a process imposes objectionable complications, difficulties and expense into printing practice. Complicated equipment must be provided for heating the print and the web. The web must be allowed to cool between impressions, necessitating additional lead over the normal of as high as 10 to 60 feet and difficulties are encountered in obtaining proper registration of contiguous or superimposed prints due to dimensional changes in the web caused by the heating and cooling operations and dehydration of the paper. The high heating temperatures and solvent fumes create fire and health hazards. Also, an inordinate amount of the paper stock is damaged in practice such that wastage of paper often amounts to as much as

10% or more and a further expense is involved in the cost of ink as occasioned by its high solvent and low pigment concentration and its low covering power.

5 Letterpress printing processes of the kind heretofore used are subject to the further disadvantage that the formulae of the inks must be adjusted in accordance with the type and speed of the press, the nature of the medium to be printed on and the ultimate use of the printed matter. This necessarily involves errors in formulating the inks and results in non-uniform printing quality. Furthermore, particularly where the drying of the print is effected by oxidation or evaporation of volatile solvents, the workability of the ink on the press and its drying characteristics are subject to change, thereby causing non-uniformity in the printing process and requiring frequent adjustment of the ink 10 formulae. Non-uniformity of operation also is caused by changing weather conditions in the pressroom and the variable moisture content of the paper.

Recently there has been developed a letterpress 25 process which involves the use of an ink which is solid at normal pressroom temperatures and melts to a fluid consistency suitable for letterpress printing at elevated temperatures, that is, temperatures in excess of 175° F. In this process, the printed ink films are set instantaneously 30 when printed without encountering the above-mentioned difficulties of known letterpress processes. The ink is heated to an elevated temperature, giving it the desired molten consistency for 35 working on the press and the inking mechanisms and the printing form of the printing-press also are heated to elevated temperatures. The ink in molten condition is applied to the printing surface of the form in thin films which adhere to 40 the printing surfaces at elevated printing temperatures even though the films of ink are quite fluid and the form may be moving at high speed. A sheet or web to be printed is impressed by the inked form, the sheet or web being at ordinary 45 pressroom temperatures or at any other temperatures which are low in relation to the temperature of the molten ink. In this way, the ink is printed from the relief surfaces of the form onto the sheet or web in thin hot films and the extraction of heat from these thin films into the 50 web causes the print to set by freezing instantaneously upon leaving the printing surfaces. Further cooling of the resultant printing either by natural cooling or by artificial cooling in high 55 speed printing work produces a finished print im-

mediately after the printing operation, which is rigid and resistant to smearing, marring and offsetting during succeeding impressions and during the folding, stacking and assembling of the printed matter in further operation of the press.

Satisfactory operation of the above-described process of cold set letterpress printing requires that the ink be delivered to the plate cylinder at a given temperature within a narrow range and be maintained within such temperature range until it is applied to the paper. Also, the temperature of the film of ink supplied to the plate cylinder must be substantially uniform throughout its width. Existing printing presses may be used for printing according to the cold set letterpress process upon being equipped with means for conditioning the ink to deliver it to the plate cylinder at the proper temperature and to so equip the machines involves the provision of heating means in the ink distribution systems. Such systems consist essentially of an ink fountain or ink-furnishing element, together with a plurality of hollow metal rollers cooperating with a plurality of rubber or composition rollers to convey the ink from the fountain or furnishing element to the plate cylinder and simultaneously work it into proper consistency for application to the type on the plate cylinder.

An object of this invention is the provision of heating equipment in the ink distribution system of such character that it is effective to heat the ink in the fountain to proper temperature within a narrow predetermined range and maintain the ink within said temperature range until the ink is applied by the plate cylinder to the paper.

According to this invention, means are provided for circulating hot liquid, preferably hot water, through some, or preferably all, of the hollow metal rollers of the ink distributing system and the printing cylinder and in heat exchange relation to the ink fountain or ink furnishing element. The printing cylinder and each heated roller is maintained full of hot liquid so that heat is constantly supplied to the entire inner peripheral surface, and the hot liquid is caused to flow therethrough at such rate that a heat balance is maintained. The rate of flow of the hot liquid is controlled by the size of the outlet orifice which is so dimensioned that the heat dissipation is balanced by the heat supplied by the liquid. The piping for effecting circulation of the hot liquid is so arranged that the direction of flow of the hot liquid alternates in the rollers and cylinder in the order of contact by the ink film, thereby effecting substantially uniform distribution of heat supply laterally across the ink film, resulting in substantially uniform temperature laterally of the film. Means are provided in the circulation system for effecting removal of air or other gas from the circulating liquid to prevent air binding and its attendant consequences. When water is used as the heating liquid, temperatures in excess of 212° F. are obtainable by operation of the system under suitable super-atmospheric pressure. If the system is operated at a pressure higher than 15 pounds above atmospheric pressure, special equipment is required, but for lower pressures standard equipment is used. Instead of using hot water under pressure, where temperatures in excess of 212° F. are desired, use may be made of well-known liquids having sufficiently high boiling points under either atmospheric or super-atmospheric pressure.

Other objects, novel features and advantages of this invention will become apparent from the following specification and accompanying drawings, wherein:

5 Fig. 1 is a diagrammatic sectional view through an ink distributing system embodying the invention;

Fig. 2 is a plan view thereof;

10 Fig. 3 is a schematic view of said system illustrating one form of liquid heating equipment;

Figs. 4 and 5 illustrate other forms of heating equipment for the system;

15 Fig. 6 is a diagrammatic view of a system operating under pressures in excess of 15 pounds above atmospheric, and

Fig. 7 is a diagrammatic view of a modified pressure-type system.

In Fig. 1 is illustrated a typical ink distribution system consisting of a plurality of rotatable hollow metal rollers R and R₁, a plurality of rubber or composition rollers R₂, an educator roller R₃ and a fountain roller R₄. Means (not shown) are provided for rotating said rollers in timed relation and for effecting axial vibration of certain of said rollers, all as is standard practice in such ink distribution systems. The fountain roller R₄ is partially immersed in a pan or fountain F and certain of the rollers R₂ contact the printing surface on the printing cylinder P, between

20 which and the impression cylinder C passes a web W of paper or other similar material to be printed. A jacket J partially encloses the pan or fountain F and in the jacket J is arranged a pipe or a pipe coil 10. The jacket J is filled with 30 suitable liquid for effecting transfer of heat from the coil 10 to the pan F and its contents. Ink is delivered by the educator R₃ from the fountain roller R₄ to the roller R. From the roller R, ink is supplied by the rollers R₂ to the two rollers R₁ 40 and through additional rollers R₂ from the rollers R₁ to the printing cylinder P.

A header consisting of a cross-pipe 11 and two arms 12 and 13 is supplied with hot liquid through a pipe 14. Pipes 15, 16 and 17 lead from 45 the arm 12 respectively to one end of the coil 10, one end of the roller R and one end of the printing cylinder P. Pipes 18, 19 and 20 lead from the arm 13 to the opposite ends of the fountain roller R₄ and both rollers R₁. A discharge header consists of a cross-pipe 21 and two arms 22 and 23 and liquid is discharged from this header through the pipe 24. Pipes 25, 50 26 and 27 lead respectively from the opposite ends of the coil 10, roller R and printing cylinder 55 to the branch 22, and pipes 28, 29 and 30 lead respectively from the opposite ends of the fountain roller R₄ and both rollers R₁ to the arm 23. The direction of flow in the coil 10, the roller R and the cylinder P is opposite to the direction of flow in the roller R₄ and the rollers R₁.

60 Each of the aforementioned pipes is connected to the associated roller or cylinder by a standard coupling which permits free rotation relative to the pipe. Such a coupling is standard article of merchandise and is not herein disclosed in detail as the particular construction of such coupling forms no part of the present invention.

The rate of flow of hot liquid through the coil 10, each distribution roller and the printing cylinder is controlled by the outlet orifice therefor. Such orifice may be of fixed size or may be in the nature of a valve 31, whereby the rate of flow may be varied. In each case, the inlet orifice is of larger area than the outlet orifice and 70 has no function in controlling the rate of flow.

With such arrangement of inlet and outlet orifices, there is no possibility of the occurrence of air pockets or vacuum in the cylinders as liquid is always supplied thereto at least as fast as it is removed therefrom.

Referring now to Fig. 3, the pipe 24 leads to the inlet of a tank T, the outlet of which communicates with the inlet of a pump B and the outlet of said pump communicates with the pipe 14. Operation of the pump B withdraws liquid from the tank T and supplies such liquid through the pipe 14 to the coil 10, the distribution rollers and the printing cylinder from which the liquid is returned to the tank through the pipe 24. A steam coil arranged in the tank T is supplied with steam through a pipe 33 from any suitable source (not shown) and a pipe 34 returns condensate from the coil to such source. A thermostat 35, arranged in the tank 32, operates a valve 36 by which the supply of steam to the coil 32 is controlled to maintain the liquid at constant temperature.

A pipe 37 leads from the top of the tank T to a second tank T₁ at a higher elevation than the tank T, the tank T₁ being provided with an air vent 38. A valve-controlled liquid supply pipe 39 communicates with the pipe 37 below the tank T₁. The operating pressure of the system is determined by the level of the liquid in the tank T₁, which must be at least high enough to insure complete filling of the rollers and cylinder.

Figs. 4 and 5 illustrate modified forms of equipment for heating the liquid in the tank T. In the modification of Fig. 4, steam is introduced into the interior of the tank, through the extension 33a of the pipe 33, and the valve 36 is operated by the thermostat 35 to regulate the amount of steam supplied to maintain the liquid in the tank at the proper temperature. Air introduced into the tank with the steam is vented through the pipe 37 as previously described.

In the modification of Fig. 5, a burner 40, preferably an oil burner or gas burner, is arranged in the bottom of the tank and is supplied with fuel through the pipe 41 equipped with a valve 42. The combustion gases from the burner pass 43 arranged in the tank and escape through the flue 44, the combustion gases thus being in heat exchange relation to the liquid in the tank. The valve 42 is operated by a thermostat 35 to regulate the flow of fuel to the burner 40 to maintain the liquid in the tank T at proper temperature.

In the operation of the system, any air trapped in the rollers is dissipated in the circulating liquid and is carried thereby into the tank T, from which it escapes through the pipe 37 and vent 38. Also, any air carried into the system by the original or make-up liquid introduced through the pipe 39 is similarly vented. After a short period of operation, all air is removed from the system, thus insuring uniform transfer of heat from the liquid to the surface of the rollers.

The liquid in the tank T is maintained at constant temperature by operation of the valve 36 by the thermostat 35. Constant temperature liquid is thus supplied to the coil 10, the plate cylinder P and the rollers of the distribution system. The rate of flow through each roller and the printing cylinder is controlled by the respective outlet orifices to be such as to supply sufficient heat thereto to maintain a heat balance therein with a temperature differential of not more than 10° F. and preferably of not more

than 2° F. between the opposite ends thereof. The heat supplied to the rollers and the plate cylinder is so distributed and balanced that there is little or no temperature differential, either laterally or circumferentially, along the surface of any roller or the cylinder or along the ink film. This is accomplished (1) by maintaining a large mobile or self-equalizing mass of heat in each roller and the cylinder in the form of a body of hot liquid (2) by maintaining at a constant temperature all liquid circulated into the rollers and the cylinder (3) by keeping at a minimum (not more than 30° F. and in some instances not more than 2° F.) the differential between the temperature of the liquid and the desired temperature of the ink (4) by keeping the rate of liquid circulation, through the use of ample pumping capacity, high enough to prevent substantial drop in the liquid temperature during its passage through any roller or the cylinder (5) by selecting an outlet orifice size for the rollers and cylinder in relation to the rate of liquid circulation so that the mass of liquid in each roller and the cylinder is constantly subject to uniform and positive pressure, and (6) by alternating the direction of flow of the circulated liquid through the various rollers and cylinder in the order of contact by the ink. In this way, the ink may be maintained at substantially the same desired temperature from its departure from the fountain until after it is applied to the web.

The maximum temperature to which the liquid in the tank can be heated is determined by the boiling point of the liquid at the operating pressure of the system as above such temperature vaporization of the liquid will occur. Usually fifteen pounds above atmospheric pressure is the maximum allowed by law where ordinary plumbing equipment is used, and with water as the heat supplying liquid, the maximum temperature obtainable at such pressure is approximately 250° F. and the operating pressure is obtained by having approximately 34 feet of liquid head in the tank T₁. With other liquids having higher boiling points than water, operating temperatures in the range of 250° F. to 500° F. may be obtained in this system. The liquid may be heated to temperatures in excess of 212° F. by use of superheated steam as the heat source or by use of the heater illustrated in Fig. 5.

Fig. 6 illustrates a system having an operating pressure in excess of fifteen pounds above atmospheric. In such a system, the equipment used is of the so-called pressure vessel type which is sanctioned by law for high pressures. The pipe 37 is equipped at its upper end with an air vent 45 of such nature as to permit the escape of air while preventing the escape of liquid. A safety valve 46 is connected to the system, preferably to the pipe 37, and determines the maximum pressure permissible in the system. A vertical cylinder 47 is connected at its lower end to the pipe 37 by a pipe 48. In the cylinder 47 is provided a piston 49 equipped with a weight 50. The mass of the weight determines the operating pressure of the system. Any other suitable pressure maintaining means may be substituted for the cylinder and weight piston such, for example, as a cylinder with an air chamber.

Any suitable liquid may be used as the heating medium in the above-described system under the required pressure to maintain the boiling point of such liquid above the desired operat-

ing temperature. By use of water as the heating liquid, operating temperatures in the range of 250° F. to 500° F. are obtainable by maintaining the operating pressure in the range of 30 pounds to 679 pounds.

The operation of the system illustrated in Fig. 6 is the same as previously described, except that the operating pressures and temperatures are higher. The rate of flow through the various units is controlled by the outlet orifices 31 to maintain heat balance with a temperature differential not exceeding 10° F. and the direction of flow alternates in successive units. Also, air is removed from the rollers and air introduced into the system with the liquid escapes 15 through the pipe 37, and air vent 45.

With certain types of thermo fluid inks, the printability thereof is substantially the same over a fairly wide temperature range and in connection with the use of such inks close control of the temperature of the rolls is not essential, nor is it essential that the rolls be of substantially uniform temperature throughout their length. The apparatus illustrated in Fig. 7 is designed for use with such inks. In this apparatus, a mixture of vapor, air and water is provided in the coil 10, printing cylinder P and the ink feeding rollers R and R₁. As close regulation of temperature is not required it is not necessary to provide for high efficiency heat transfer from the heating fluid to the rollers and cylinder. Therefore, it is not essential that the heating fluid be air free as the effect of the reduced heat transfer efficiency by reason of the presence of air in the fluid is relatively unimportant in the operation of printing with inks of the character above referred to. Also, for similar reasons, it is not essential that the rollers be kept full of substantially constant temperature liquid.

Referring to Fig. 7, the equipment illustrated is of the so-called pressure vessel type which is sanctioned by law for high pressure operation. A tank 60 has a vertical pipe 61 leading from its highest point and at its upper end the pipe is connected to the low pressure side of a pressure reduction valve to the high pressure side of which is attached a water supply pipe 63. A safety valve 64 is connected to the pipe 61 below the pressure reduction valve 62. In the tank 60 is preferably provided a heating coil 65 through which superheated high pressure steam is circulated by means of the pipes 66 and 67 but any other suitable heating means may be employed. A pipe 14' leads from the top of the tank 60 to the supply header 11 described in connection with the previous figures, while a pipe 24' leads from the discharge header 21, also previously described, to the inlet port of a pump B', the outlet port of which discharges into the tank 60.

In operation, the tank 60 contains water under super-atmospheric pressure. Whenever the pressure in the system drops below that for which the valve 62 is set, additional water is automatically introduced into the system to bring the pressure up to the predetermined value. The safety valve 64 is set to function at some pressure in excess of the predetermined pressure just referred to.

The water in the tank 60 is heated by passing steam through the coil 65 and the supply of steam is so regulated as to maintain the water in the tank at a predetermined temperature. The temperature maintained in the tank 60 is suf-

ficient to cause vaporization of the liquid therein with the result that water vapor is caused to flow through the pipe 14 and to be supplied to the various units of the ink distribution system.

5 In the ink distribution system, the vapor is condensed and the condensate is withdrawn through the pipe 24' and is returned to the tank 60 by the pump B'. The amount of condensate in the rollers and cylinder depends upon the location of the outlet therefrom. However, in any event, each roller will contain a certain amount of condensate together with air and vapor. Any air escaping from the rollers is returned to the tank 60 along with the condensate and air, as well as vapor, passes from the tank 60 to the distribution system. In a modified form, a vapor trap may be substituted for the pump B' in which event the condensate is not returned to the tank 60 but is allowed to flow 10 to some source of low pressure, such, for example, as the sewer.

I claim:

1. In letterpress printing with ink solid at normal pressroom temperature and liquid at elevated 25 temperature wherein the ink is liquefied by heating, supplied from a fountain and transferred in film form to a hollow printing cylinder by a distribution system including a plurality of hollow rollers, the method which comprises recirculating a definite volume of liquid in heat exchange relation to the ink fountain and through said rollers and cylinder in parallel streams with the direction of liquid flow alternating in the rollers and cylinder in the order of contact by the ink 30 film, maintaining said liquid at sufficient pressure that its boiling point exceeds the printing temperature of the ink, heating said liquid to a temperature exceeding the printing temperature of the ink and exceeded by the boiling point of 35 the liquid, controlling the outflow of liquid from said rollers and cylinder to maintain therein a body of liquid in contact with entire inner surfaces of said rollers and cylinder, and regulating the flow rate through said rollers and cylinder to 40 maintain heat balance therein with not more than 10° F. differential between the inlet and outlet ends thereof.

2. In letterpress printing with ink solid at normal pressroom temperature and liquid at elevated 50 temperature wherein the ink is liquefied by heating, supplied from a fountain and transferred in film form to a hollow printing cylinder by a distribution system including a plurality of hollow rollers, the method which comprises recirculating a definite volume of liquid in heat exchange relation to the ink fountain and through said rollers and cylinder in parallel streams with the direction of liquid flow alternating in the rollers and cylinder in the order of contact by the ink 55 film, heating said liquid to a temperature in the range of 150° F. to 250° F., controlling the outflow of liquid from said rollers and cylinder to maintain therein a body of liquid in contact with the entire inner surfaces of said rollers and cylinder, and regulating the flow rate through said rollers and cylinder to maintain heat balance 60 therein with not more than 10° F. differential between the inlet and outlet ends thereof.

3. In letterpress printing with ink solid at normal 65 pressroom temperature and liquid at elevated temperature wherein the ink is liquefied by heating, supplied from a fountain and transferred in film form to a hollow printing cylinder by a distribution system including a plurality of hollow rollers, the method which comprises recircu-

lating a definite volume of liquid in heat exchange relation to the ink fountain and through said rollers and cylinder in parallel streams with the direction of liquid flow alternating in the rollers and cylinder in the order of contact by the ink film, maintaining said liquid at sufficient pressure that its boiling point exceeds the printing temperature of the ink, heating said liquid to a temperature in the range of 250° F. to 550° F. prior to supplying the same to said rollers, cylinder and fountain, controlling the outflow of liquid from said rollers and cylinder to maintain therein a body of liquid in contact with the entire inner surfaces of said rollers and cylinder, and regulating the flow rate through said rollers and cylinder to maintain heat balance therein with not more than 10° F. differential between the inlet and outlet ends thereof.

4. In letterpress printing with ink solid at normal pressroom temperature and liquid at elevated temperature wherein the ink is liquefied by heating, supplied from a fountain and transferred in film form to a hollow printing cylinder by a distribution system including a plurality of hollow rollers, the method which comprises recirculating a definite volume of liquid in heat exchange relation to the ink fountain and through said rollers and cylinder in parallel streams with the direction of liquid flow alternating in the rollers and cylinder in the order of contact by the ink film, controlling the outflow of liquid from said rollers and cylinder to maintain therein a body of liquid in contact with the entire inner surfaces of said rollers and cylinder, heating said liquid to supply a body of mobile liquid in heat exchange relation with the walls of said rollers and cylinder, flowing the liquid through said rollers and cylinder at a rate sufficient to prevent substantial temperature drop between the ends thereof, and maintaining the temperature of the liquid supplied to the rollers and cylinder not more than 30° F. above the desired printing temperature.

5. In a printing press comprising a hollow printing cylinder, an ink furnisher, means including hollow metal rollers for conveying an ink film from said furnisher to said cylinder and a system for circulating liquid through said furnisher, rollers and cylinder; a closed tank containing a body of liquid, means for heating said body of liquid, a pump and manifolds connecting said tank with said ink furnisher, rollers and cylinder for recirculating liquid from said tank in parallel streams in opposite directions through alternate members of said ink furnisher, rollers and cylinder back to said tank to effect uniform lateral distribution of heat in said film, and means for controlling flow through said rollers and cylinder to maintain constant positive pressure therein exceeding the pressure beyond the outlets therefrom.

6. In a printing press comprising a hollow printing cylinder, an ink furnisher, means including hollow metal rollers for conveying an ink film from said furnisher to said cylinder and a system for circulating liquid through said furnisher, rollers and cylinder; a closed tank containing a body of liquid, means for heating said body of liquid, a pump and manifolds connecting said tank with said ink furnisher, rollers and cylinder for recirculating liquid from said tank in parallel streams in opposite directions through alternate members of said ink furnisher, rollers and cylinder back to said tank to effect uniform lateral distribution of heat in said film, means for controlling flow through said rollers and cylinder to maintain constant positive pressure therein exceeding the pressure beyond the outlets therefrom, and means for maintaining the liquid in said tank at constant temperature.
7. In a printing press comprising a hollow printing cylinder, an ink furnisher, means including hollow metal rollers for conveying an ink film from said furnisher to said cylinder and a system for circulating liquid through said furnisher, rollers and cylinder; a closed tank containing a body of liquid, means for heating said body of liquid, a pump and manifolds connecting said tank with said ink furnisher, rollers and cylinder for recirculating liquid from said tank in parallel streams in opposite directions through alternate members of said ink furnisher, rollers and cylinder back to said tank to effect uniform lateral distribution of heat in said film, means for controlling flow through said rollers and cylinder to maintain constant positive pressure therein exceeding the pressure beyond the outlets therefrom, means for maintaining the liquid in said tank at constant temperature, and means for maintaining the liquid in said tank under constant super-atmospheric pressure.

8. In a printing press comprising a hollow printing cylinder, an ink furnisher, means including hollow metal rollers for conveying an ink film from said furnisher to said cylinder and a system for circulating liquid through said furnisher, rollers and cylinder; a closed tank containing a body of liquid, means for heating said body of liquid, a pump and manifolds connecting said tank with said ink furnisher, rollers and cylinder for recirculating liquid from said tank in parallel streams in opposite directions through alternate members of said ink furnisher, rollers and cylinder back to said tank to effect uniform lateral distribution of heat in said film, means for controlling flow through said rollers and cylinder to maintain constant positive pressure therein exceeding the pressure beyond the outlets therefrom, means for maintaining the liquid in said tank at constant temperature, and means for automatically venting air from said tank.

LYNN B. CASE.
